BOTTLE CLOSURE OR SIMILAR ARTICLE

Robert A. Roth, 15 E. 41st St., New York, N.Y. 10017

Filed Sept. 10, 1965, Ser. No. 86,925

Term of patent 14 years

(Cl. D58—26)

FIG. 1

FIG. 3

FIG. 2

FIG. 4

FIG. 5

FIG. 1 is a side elevational view of a bottle closure or similar article showing my new design;

FIG. 2 is a top plan view thereof;

FIG. 3 is a bottom plan view thereof;

FIG. 4 is an elevational view thereof with the upper part of the closure broken away and sectioned; and

FIG. 5 is a top perspective view thereof.

The dominant features of my design are shown in full lines and reside primarily in the proportional relationship between the skirt portion and flare portion in combination with the recessed substantially flat portion.

I claim:

The ornamental design for a bottle closure or similar article, as shown and described.
